UNITED STATES PATENT OFFICE.

JOHN B. MORGAN, OF PHILADELPHIA, PENNSYLVANIA.

DESIGN FOR WOVEN FABRIC.

SPECIFICATION forming part of Design No. 23,837, dated December 4, 1894.

Application filed October 29, 1894. Serial No. 527,358. Term of patent 7 years.

To all whom it may concern:

Be it known that I, JOHN B. MORGAN, a citizen of the United States, residing in Philadelphia, Pennsylvania, have invented a certain 5 Design for Ticking and other Woven Fabrics, of which the following is a specification.

My design for ticking or similar woven fabric, is illustrated in the accompanying drawing, which shows two complete sets of stripes.

10 The essential feature of this design is the tinted back ground having the prominent wide and narrow stripes alternating with each other and the heron-bone effect found in the narrow stripe.

15 D is the tinted back ground, E the wide stripe and F the narrow stripe. The wide stripe is somewhat darker than the back ground and has a series of very narrow light stripes e alternating with very narrow dark 20 stripes e'. Running through the dark stripes

are light dots giving the effect clearly shown in the drawing.

The narrow stripe F consists of a central dark stripe f and two stripes f' f' on each side of the dark stripe and each stripe f' is 25 made up of a series of inclined transverse stripes and separated from the dark stripe by very narrow stripes f² giving the heron bone effect mentioned above.

I claim—

30 The design for ticking or other fabric as herein described and illustrated in the accompanying drawing.

In testimony whereof I have signed my name to this specification in the presence of 35 two subscribing witnesses.

JOHN B. MORGAN.

Witnesses:

WILL. A. BARR,
JOSEPH H. KLEIN.
